UNITED STATES PATENT OFFICE.

LUTHER E. GROAT AND FREDERICK F. BRUSH, OF LOS ANGELES, CALIFORNIA,
ASSIGNORS TO ELEVATOR SAFETY APPLIANCE COMPANY, A CORPORATION
OF CALIFORNIA.

ELEVATOR-DOOR-OPERATING DEVICE.

1,400,215.

Specification of Letters Patent. Patented Dec. 13, 1921.

Application filed May 26, 1919. Serial No. 299,979.

To all whom it may concern:

Be it known that we, LUTHER E. GROAT and FREDERICK F. BRUSH, both citizens of the United States, and both residing at Los Angeles, in the county of Los Angeles, State of California, have invented a new and useful Elevator-Door-Operating Device, of which the following is a specification.

Our invention relates to elevators, and 10 more particularly to the doors closing the door openings into the elevator hatchways.

An object of the invention is to provide means by which these doors can be opened and closed by power and by which interlocking means are provided by which safety 15 of operation is assured. These interlocks include means for inhibiting the opening of the door at all times that the car is in motion and at all times that the car is at 20 rest except when it registers properly with a floor. The interlocks also include means for shutting off power from the door closing mechanism in the event that the door meets an obstruction, as for instance, if it, by accident, 25 closes on a person, and means for locking the car in position at the floor at all times except when the door is closed.

A further object of the invention is to provide a door closing mechanism which will 30 start the door from a position at rest and accelerate it uniformly and smoothly, decelerating to a second position of rest with a large excess of power on either end of the stroke.

35 A further object of the invention is to provide a door operating device which may be driven by an electric motor and in which the interlock features necessary in connection with such a device are applied to the 40 electric circuit of that motor.

A further object of the invention is to provide a mechanism for opening and closing the doors which will have a small number of parts and be very rugged and compact in 45 construction.

A further object of the invention is to provide a novel means for oiling.

A further object of the invention is to provide a door operating mechanism which 50 is carried on the elevator car and which

successively comes into position opposite a door locking and moving device at each door, together with means for throwing said mechanism into operative relationship with said device when it is desired to operate the 55 door, said mechanism having at all other times a considerable clearance from said device.

Further objects and advantages will be 60 made evident hereinafter.

Referring to the drawings, which are for illustrative purposes only,

Figure 1 is a somewhat diagrammatic view of an elevator hatchway with a car in place therein.

Fig. 2 is a front view of the same parts showing the method of operating the door.

Fig. 3 is a side view partly in section of the elevator door operating mechanism.

Fig. 16 is a section on a plane represented 95 by the line 16-16 of Fig. 15.

In Fig. 1 an elevator hatchway is shown in which a car 22 is moved by means of a hydraulic plunger 23, a hydraulic elevator being selected merely for convenience of illustration, our invention being applicable as will readily be understood to any type of 100

elevator. Located at each of the floors 24 is a door 25 and a door actuating and locking device 26. Carried on the top of the car is a door operating mechanism 27. The door actuating and locking devices 26 operates the door through a throw bar 28 pivoted to the building structure at 29, the throw bar being driven through a toggle 30 composed of two links 31 and 32 which may be broken if necessary from the inside of the hatchway, or with certain limitations from the outside of the hatchway, to allow the door to be opened in the event that the actuating device becomes inoperative for any reason. The driving toggle 30 is so constructed that it is rigid at all times except when manually operated to allow the door to be opened. A counter weight 33 is provided on an extension 34 of the throw bar 28 so that the door at all times tends to close under the action of gravity, the door being shown in closed position in Fig. 2, the open position being indicated by dotted lines 35 in that figure. The door locking device is provided with projections 36 and 37 by means of which the door is interlocked, locked and moved as will hereinafter be explained.

The door operating mechanism 27 illustrated in detail in Figs. 3 to 7 inclusive consists of a main frame 40 having journaled in the upper portion thereof a worm shaft 41 carrying a worm 42 and mounted in any suitable form of bearings such as shown. The shaft 41 is driven by an electric motor 43 and is provided with a magnetic brake 44. The magnetic brake 44 consists of a brake wheel 45, brake shoes 46 pivoted at 47 and connected to cores 48 and 49 which extend inside a coil or solenoid 50. The cores 48 and 49 are held apart by springs 51, and when so held apart, the shoes 46 contact with the wheel 45 giving the braking action. Whenever the coil 50 is energized the cores 48 and 49 exert a mutual attraction, being pulled inwardly until the ends of the brake shoes 46 strike against the frame 52 in which the whole device is carried. The coil 50 is connected in series with the field 53 of the motor 43, the armature of which is shown at 54 in the diagrams.

Meshing with the worm 42 is a worm gear 60, this gear being keyed on a main shaft 61 carried in bearings 62 and 63 supported by the main frame 40. The outer end of the shaft 61 and the bearing 62 is protected by a suitable dust cap 64. Mounted on the opposite end of the shaft 61 is a crank 65 having a crank pin 66 projecting from the extreme outer end thereof. The crank pin 66 turns in a crank pin block 70 which is free to slide up and down in a cross-head 71, this cross-head having a T shaped bottom 72 fitting in a slide formed in the bottom of the frame 40, being retained in place therein by a plate 73. The cross-head 71 is thus

free to slide horizontally in the frame 40 under the action of the crank pin 66 and the crank pin block 70.

The crank pin block 70 is beveled off at either side thereof as shown at 69, and fingers 74 and 75 pivoted on pins 76 carried in the cross-head 71 rest against these beveled surfaces 69. Each of the fingers 74 and 75 has secured in slots formed therein, by means of cotter pins 77, a flat strip of metal, one of these members 78 being hereinafter referred to as a closing driving strip and the other member 79 being referred to as an opening driving strip. Secured to a pin 80 on the finger 75 is an opening tension spring 81, having its other end secured on a pin 82 secured in the cross-head 71. A closing tension spring 83 is secured on a pin 84 carried by the finger 74, the other end being secured on a pin 85 carried on the cross-head 71. The spring 81 is so constructed that it is slightly stronger than necessary to open the door, and the spring 83 has approximately twice the tension of the spring 81. The driving strips 78 and 79 project outwardly from the side of the mechanism so that they can readily engage the projections 36 and 37 as will hereinafter be explained.

Secured by means of rivets 90 to the crank 65 is a cam plate 91, this plate having a cam surface 92 formed on its outer edge terminating near either end thereof in a right-angle portion 93. Secured by means of screws 94 and 95 to the cam plate 91 are auxiliary cams 96 and 97. These cams are provided with inclined surfaces 98 and 99 which in effect may be adjustable continuations of the surface 92 and form one side of grooves 100 and 101 whose purpose will hereinafter be explained.

Turning freely in the frame 40 are three shafts 110, 111 and 112 located as shown in Fig. 5. Each of these shafts is provided with a crank arm carrying pins 113, 114 and 115, these pins fitting in the grooves 100 and 101 previously described. Each of the shafts 110, 111 and 112 carries an arm 120 to which is fixed a moving contact as shown in Fig. 10. These moving contacts with their co-operating stationary contacts will, for convenience, be referred to as the closing limit switch 121, the opening limit switch 122 and the interlock switch 123 whose method of operation and purpose will be described in connection with the diagrams. The switches 121, 122 and 123 are carried in switch boxes 125 carried as shown in Figs. 3 and 6 on the frame 40.

The finger 75 is provided with a stop 130 to limit its outward movement and with a small lug 131 which rests against a bar 132. The finger 74 is provided with a stop 133 and with a lug 134 which rests against a bar 135. The bars 132 and 135 are bent as shown in Fig. 4, being pivoted at 136 so that the for-

ward portion thereof can move up and down. The bars 132 and 135 are normally held together by a tension spring 137 and each of these bars is connected through a rod 138 or 5 139 with contacts placed in switch boxes 140, these contacts forming a floor registering switch 150 and door jamb switch 151, the upper bar 132 operating the floor registering limit switch 150 and the lower bar 135 operating 10 the door jamb switch 151, these switches being closed when the bars 132 and 135 are in the normal position shown in the drawings. The floor registering limit switch 150 is open whenever the finger 75 passes inwardly 15 beyond its proper position thus lifting the bar 132 by means of the lug 131, the object of this device being to open the switch 150 whenever the opening driving strip 79 fails to find the projection 37 in its proper position. The switch 151 is open whenever the door jams, thus exerting an excessive pressure 20 on the spring 83, which may occur if the door closes on a person.

The frame 40, as will be noted, is entirely 25 inclosed except on the front, this front being partially closed by a plate 152 which extends down into such a position as to leave an open slot 153 through which the strips 78 and 79 project. Located below these strips is a wall 30 154 having an inclined edge 155. Oil being placed in the bottom of the frame 40 is carried up by the crank pin block 70 and the gear 60 and the cam plate 91 so that the whole interior of the mechanism is at all 35 times well lubricated, the parts being so formed that any drip from the mechanism is returned to the bottom of the frame 40.

Any convenient means may be provided 40 for locking the individual doors and for actuating these doors through the medium of the driving strips 78 and 79. The apparatus illustrated in Figs. 11 to 16 inclusive is a convenient method for accomplishing this result.

This mechanism consists of a pair of stationary slides 160 and 161 held together at either end thereof by blocks 162, the blocks 162 being each secured to a plate 163 by means of bolts 164. The plates 163 form a part of or are secured to the building structure by any convenient means. Moving inside the slides 160 and 161 is a casting 166 which carries a main pin 167 on which a main lever 168 is pivoted. This main lever has formed thereon the projections 36 and 37 55 previously referred to, these projections being beveled as shown at 169 and having the relative length shown in Fig. 11.

Carried in the opposite end of the lever 168 is a roller 170 which presses against an upper link 171 pivoted on a pin 172 carried in the casting 166, the line of contact between the upper link 171 and the roller 170 being inclined as shown at 173 in Fig. 14. Pivoted in the upper link 171 by means of a pin 175 60 is a lower link 176 which is in turn pivoted on

a pin 177 carried in a shoe 178 which in turn is pivoted on a pin 179 carried in the casting 166. The shoe 178 is provided with a gripping surface 180 which is straight and practically parallel with the line of motion of the casting 166 when the toggle formed by the members 171 and 176 is closed in the position shown in Fig. 15. This gripping surface 180 is caught by a roller 181 carried in a guide 182 and held in the position shown by 75 a compression spring 183, the limit of its motion being governed by an adjustable nut 184 on the outer end of a stem 185 which passes through one of the members 162. The roller 181 also is in contact in this position 80 with an inclined surface 190 formed on the lower slide 161. It will be seen that with the parts in the position shown in Fig. 15 any attempt to move the door in the direction of the arrow "A" will force the roller 181 into 85 jambing relationship between the surfaces 180 and 190 thus effectually locking the door against any movement.

It will be further evident that whenever the main lever 168 is rotated in the direction 90 of the arrow "B" around the pin 167 that the roller 170 acting on the inclined surface 173 will break the toggle, pulling the surface 180 out of contact with the roller 181 and allowing the door to be freely 95 opened.

It will be further evident that by making the surface 180 of some length that this locking action can take place in any one of several different positions thus allowing the 100 door to be locked even if it is not entirely closed.

A buffer spring 195 is provided to determine the position at rest of the casting 166 with relation to the end member 162. A pin 105 196 is provided to which the toggle member 32 is pivoted.

The method of electrical connection when applied to an electric elevator is illustrated in Fig. 9, in which 200 and 201 are supply 110 wires feeding through a switch 202 and fuses 203. The supply wire 201 is connected by a wire 207 to one of the stationary contacts of a counter electro-motive force relay 205. The other stationary contact of 115 the counter electro-motive force relay 205 is connected to a wire 208. The relay 205 has a coil 206 connected across the armature 209 of the main driving motor of the elevator, the relay 205 being so constructed that 120 the circuit between its stationary contacts is open whenever the voltage across the armature is above a predetermined value. This value may be conveniently set at approximately ten per cent. of the normal 125 voltage impressed on the armature, the relay then being held open due to the counter electro-motive force generated in this armature even when the motor is disconnected from the line so long as the armature is in 130

motion. In other words, the relay 205 is open at all times except when the motor is at rest or just about to come to rest, the object of the relay 205 being to entirely cut off the door operating device at all times when the elevator is in motion.

A car switch 210 is provided for manually interrupting the wires 200, 201 and 208 and a series of fuses 211 is inserted in the wire 201 which is connected to the series field 53 of the motor 54. The other terminal of the series field 53 is connected through the brake coil 50 by means of a wire 212 to the two contacts 213 and 214 of an opening relay 215 and a closing relay 216. The armature 54 of the door operating motor is connected on one side to a wire 217 with the contacts 218 and 219 of the closing relay 216, the other side of the armature 54 being connected through a wire 220 with the contacts 221 and 222 of the opening relay 215. The wire 200 is connected to the contact 223 of the opening relay 215 and to the contact 224 of the closing relay 216. Bridging members 225 and 226 in the relays 215 and 216 are in contact as shown in Fig. 9 whenever the circuit to these relays is open, being pulled into an upper position whenever the coils and relays are energized.

The operating coil of the relay 215 is connected on one terminal to the floor registering switch 150 and the operating coil of the relay 216 is connected on one terminal to the door jamb switch 151. The other terminal of the coil of the relay 215 is connected through a wire 230 with a contact 231 of a door operating controller 500, the other terminal of the coil of the relay 216 being connected to a contact 232 of that controller. A contact 233 of that controller is connected through a wire 234 with the wire 200. The wire 208 is connected to the central point of the opening limit switch 122 and the closing limit switch 121. When the door is closed the limits 121 and 122 are in the position shown in Fig. 9, the circuit between the wire 208 being closed through a wire 241 with the floor registering switch 150 and the circuit through a wire 242 being open to the door jamb switch 151.

For the purpose of preventing the manual control of the elevator from being operated when the door is open or in the process of opening, we provide contacts 250 and 251 in the door operating controller 500, the contact 250 being connected through a wire 252 with one terminal of the interlock switch 123, this switch being closed when the door is closed, and being connected through a wire 253 with the elevator control cable. The contact 251 is connected through a wire 254 with the center 255 of the elevator controller so that the main circuit to the elevator control is open 60 at all times that connection is interrupted.

between the contacts 250 and 251. This occurs whenever the controller 500 is thrown open to open the door, the circuit remaining open until the door operating controller is thrown back into closed position. The controller 500 is diagrammatically illustrated, the closed position of this controller being shown by the line $x-x$, the open position being shown in the dotted lines $y-y$. Contact rings 260 which are electrically connected make contact and connection between the contacts 250 and 251 when the controller is in the closed position, contact rings 261 similarly connecting the contacts 232 and 233. The circuit between the contacts 232 and 233 and between the contacts 250 and 251 is open whenever the controller is operated to open the door, and connection between the contacts 231 and 233 being established at this time by means of rings 262 which are electrically connected. While a diagram drum top controller is shown for accomplishing this result, it is obvious that other equivalent means might be used if desired.

Our invention can also be applied with excellent advantage to a hydraulic elevator, the diagram of connections therefor being shown in Fig. 8. In this diagram of connections, main supply wires 300 and 301 are carried through a main switch 302 and main fuses 303, the wire 301 being connected to an auxiliary wire 304. The wire 301 is also carried through a water control switch 305 which is so arranged that it is closed whenever the water supply to the hydraulic plunger is shut off, being opened whenever water is turned into the plunger to operate the car. The wires 300, 304 and 301 are carried to a car switch 310. The wire 304 is connected through fuses 311 with the series field 53 of the door operating motor 54 and through the brake coil 50, and a wire 312 to the contact 313 of the opening relay 315 and the contact 314 of the closing relay 316. One terminal of the armature 54 is connected through a wire 317 with the contacts 318 and 319 of the opening relay 315, the other terminal of the armature being connected through a wire 320 with the contacts 321 and 322 of the closing relay 316. The wire 300 is connected to contact 330 of the opening relay 315 and to a contact 331 of the closing relay 316.

The door operating controller is shown 120 diagrammatically at 340, the line $x-x$ showing its closed position and the line $y-y$ its open position. Stationary contact fingers 341, 342, 343 and 344 are provided in the controller 340. The finger 341 is connected 125 through a wire 350 with the coil 351 of the opening relay 315, the other terminal of this coil being connected to a contact 352 of the interlock relay 353. The contact 342 is connected to the coil 354 of the closing re- 130

lay 316, the other terminal of this coil being connected through a wire 355 with a door jamb switch 356, the other terminal of this switch being connected through a wire 357 with one side of a closing limit switch 358. The other terminal of this switch is connected through a wire 359 with the wire 301. This wire 301 is also connected to one terminal of an opening limit switch 360, the other terminal of this switch being connected through a wire 361 with a contact 362 on the interlock 353. The contact 343 is connected through a wire 365 with a contact 366 on the interlock which is also connected through a wire 367 with a contact 368 on this interlock. The contact 370 of the interlock 353 is connected to the wire leading from the contact 342 to the closing relay coil 354. The contact 344 is connected through a wire 371 with a contact 372 of the interlock which is also connected to the coil 373 of the interlock, the other terminal of this coil being connected through a floor registering switch 374 to a wire 375 which in turn is connected into the wire 304 at a point 376 just below the car switch 310.

The controller 340 is provided with segments 380 which connect the contacts 341 and 343 when the switch is open. Contacts 381 connect the contacts 342, 343 and 344 all together when the switch is closed. For the purpose of providing locking means for the operating lever of the elevator we provide a double throw interlock switch 390, the center of which is connected through a wire 391 to any suitable source of electric power, this switch being adapted to be thrown either to a contact 392 connecting an interlock coil 393 on the operating lever or to a contact 394 connected to the threshold light 395, the other terminals of the coil 393 and the threshold light 395 being connected to the other source of power. Whenever the coil 393 is energized, the manual operating lever of the elevator may be moved, but when this coil is deenergized the manual operating lever of the elevator is locked.

The method of operation of an electric elevator having the diagram of connections illustrated in Fig. 9 will now be described.

The elevator being at rest at any floor it is desired to go to any other floor. The controller 255 is then manipulated to control the armature 209 by any convenient method of connection not shown. Whenever voltage is placed across the armature 209, the coil 206 is energized and the circuit between the stationary contacts of the counter electro-motive force relay 205 is broken thus effectively shutting off any circuit through the wires 207 and 208 and preventing the operation of the door operating mechanism. The car is moved to the floor at which it is desired to stop and the con-

troller 255 is manipulated to bring the car to rest, current being thus shut off from the armature 209. The counter electro-motive force relay 205 will, however, be held up as long as the armature 209 turns even if the armature 209 is disconnected from the source of power, the counter electro-motive force of the armature being sufficient to hold the relay 205 open until the armature 209 practically comes to rest, the stationary contacts of the relay 205 then being bridged. The stationary contacts of the relay 205 being thus closed it is possible to get power through the control system of the door operating mechanism.

The operator then moves the controller 500 from the closed position $x-x$ to the open position $y-y$, making a connection between the contacts 231 and 232. This completes a circuit through the wire 200 and the wire 234 to the contact 233, through the movable contacts 232 and 262 to the contact 231 and through the wire 230 to the coil of the opening relay 215. The other terminal of this relay is connected to the floor registering switch 150 and through the opening limit switch 122 to the wire 208 which is connected through the counter electro-motive force relay 205 to the wire 201 which is the other side of the circuit. The counter electro-motive force relay 205 being closed, the opening relay 215 operates, providing the floor registering switch 150 and the opening limit 122 are closed which will be the case if the mechanism is in its proper position. The opening relay, if these conditions exist, will therefore lift, closing the circuit between the contacts 213 and 221. This completes a circuit through the wire 201, the field 53, the brake coil 50 and the contact 213, through the moving contact 225 and the contact 221 and through the wire 220 to the armature 54, from thence through the wire 217 to the contact 219, across the movable contact 226 of the closing relay 216 which is down, to the wire 200 thus closing the circuit through the armature 54, the series field 53 and the brake coil 50. This operates the magnetic brake 44 pulling the shoes 46 out of contact with the wheel 45 and allowing the motor 43 to drive the worm 42 in a certain direction. This direction is such that the worm gear 60 is driven in a clock-wise direction as viewed in Fig. 5, the parts at this time being in the position shown in that figure.

In the position shown in that figure the pins 115, 114 and 113 are in such a position that the closing limit switch 121 is open, the opening limit switch 122 is closed, and the interlock switch 123 is closed. As the cam plate 91 moves in a clockwise direction these switches are actuated to close the closing limit switch 121 and open the interlock 130

switch 123 from its closed position as shown in the diagram into its dotted position, thus closing the circuit to the threshold light. These switches remain in this position until 5 the cam plate 91 has practically completed its movement at which time the opening limit switch 122 is open. This opening of the opening limit switch 122 opens the circuit to the operating coil of the opening limit 10 relay 215 thus opening the circuit through the armature 54 and the brake coil 50 which stops the motor and applies the magnetic brake 44. This occurs whenever the cam plate 91 has moved through approximately 15 170 degrees. During the movement of the cam plate 91 through this 170 degrees the crank pin 66 is also moved from its position shown in Fig. 5 to a position 170 degrees in a clock-wise direction from this position. 20 In the position shown in Fig. 5 the crank pin block 70 holds the fingers 74 and 75 apart against the tension of the springs 81 and 83. This holds the driving strips 78 and 79 apart so that in their movement 25 up and down the shaft a considerable clearance is given between the driving strips and the projections 36 and 37. This obviates the necessity of accurate placing of the door actuating device and allows the car to have 30 considerable play in the hatchway without danger of the projection 36 striking upon and catching the driving strips 78 and 79 as the car passes up and down.

The driving strips 78 and 79 are formed 35 of spring material having sufficient elasticity to be considerably bent due to displacement of the members 36 and 37 without injury to the strips. They are also so formed and secured that in the event that they are struck 40 by any object projecting into the hatchway that they can be torn away without injury to any of the mechanism and can be replaced at small cost.

In its initial movement, as for example 45 from the position shown in Fig. 5 to the position shown in Fig. 3, the crank pin block 70 moves downwardly in the cross-head 71 without material movement of the cross-head 71 from left to right across the frame 40. 50 In this initial movement the fingers 74 and 75 slide downwardly on the beveled surface 69 allowing the fingers 74 and 75 to close inwardly under the action of the springs 81 and 83. This throws the driving strips 78 and 79 inwardly against the projections 36 and 37 if the car is properly registered with the floor which requires the closing of the fingers 78 and 79 on the parallel surfaces of the members 36 and 37. In the event that 55 the car is not in the proper position the finger 75 will over travel, this over travel resulting in the lug 131 lifting the rod 132 sufficiently to operate the floor registering switch 150 through the rod 139. The opening of the 60 floor registering switch 150 opens the circuit 65 to the opening relay 215 and interrupts the armature circuit and stops the motor as has already been explained.

The further movement of the crank pin 66 throws the crank pin block 70 entirely 70 out of engagement with the fingers 74 and 75 and starts the cross-head 71 to moving from right to left, as viewed in Figs. 3 and 5, in the frame 40. It should be understood that these figures are in the position as 75 viewed through the open door of the elevator, whereas the door actuating and locking mechanism illustrated in Figs. 11 to 16 inclusive is in the position as viewed from the elevator car, and movement from right 80 to left therefore of the driving strips 78 and 79 results in a movement from left to right of the door actuating mechanism. This movement first unlocks the door as has already been explained and then moves the 85 door across the opening until it is open at which time the parts are in the position shown in dotted lines in Fig. 3 and the limits operate as has been previously explained to stop the mechanism.

It will be noted that during the time that the controller 500 is in the open position, or with the stationary contacts on the line $y-y$ that the contacts 250 and 251 are open, thus opening the control circuit of the main 95 motor of the elevator through the wires 252 and 254, thus preventing any movement of the armature 207. It will also be noted that the interlock 123 also opens this circuit.

It will be noted, as has previously been 100 explained, that the spring 83 is something over twice the strength of the spring 81, therefore the spring 83 pulls the finger 74 in until a small stop formed on its face strikes against the cross-head 71 thus preventing further movement. The spring 81 then serves to take up any irregularities so that the driving strips 78 and 79 are clamped upon the members 36 and 37 preventing any lost motion therebetween, the 110 spring 81 being in function in opening and the spring 83 being in function in closing.

The door being open and the elevator being at rest on the floor and the controller 500 being in the position $y-y$, the door is 115 closed by moving this controller to the line $x-x$ or to its closing position. This closes the circuit between the contacts 232 and 233 closing a circuit from the wire 200 to the coil on the closing relay 216, this circuit being completed through the door jamb switch 151, the closing limit 121, the wire 208, the counter electro-motive force relay 205 and the wire 207 to the wire 201. In the event that the closing limit 121 is not closed or 125 the door jamb switch 151 is not closed this of course cannot occur. The actuation of the closing relay 216 completes the circuit between the contacts 218 and 214 thus closing the circuit through the series field 53, 130

the brake coil 50, to the armature 54, through the wire 217, from the armature 54, through the wire 220 to the contact 222 of the opening relay 215 across the bridging contact 225 thereof to the contact 223 and to the wire 200, thus closing the circuit through the armature 54 in a reverse direction to that previously described, causing the motor 43, through the worm 42 and the worm gear 60, to rotate the cam plate 91 and the crank pin 66 in a counter clock-wise direction as viewed in Figs. 3 and 5. This movement of the cam plate 91 actuates the limit switches 121, 122 and 123 as follows:

15 At the start of this counter clock-wise motion the closing limit switch 121 is closed, having been previously closed at the start of the opening movement. The opening limit 122 is open, this opening limit 122 being closed at the start of the closing motion. The interlock switch 123 is open making contact to the threshold light. This interlock is not closed until the cam plate 91 practically completes its movement at which

20 time the opening of the closing limit 121 shuts off current to the motor. In the reverse motion of the crank pin 66 the cross-head 71 is moved from left to right as viewed in Figs. 3 and 5 across the main frame 40, closing the door through the medium of the spring 83. The tension of the spring 83 is sufficient for any normal operation of the door.

In the event, however, that the door jams due in most cases to striking on some object in the doorway, possibly a person who has attempted to enter the elevator after the closing motion starts, the spring 83 is subjected to abnormal tension which pulls the projection on the finger 74 away from the side of the cross-head 71 and moves the lug 134 downwardly sufficiently to act upon the lower bar 135 and open the door jamb switch 151. This opening of the door jamb switch 151 opens the circuit of the coil of the closing relay 216 and opens the circuit to the armature 54 through the brake coil 50 thus shutting down the motor. If the obstruction is removed so that the tension of the spring 83 is released the door jamb switch 151 closes and reestablishes the circuit and the door continues to close. This closing motion of the door continues until the cam plate 91 reaches the position shown in Figs. 3 and 5 in which the closing limit opens and the circuit is interrupted as has previously been explained.

With the door shut, the contacts 250 and 251 being closed and the interlock 123 having been reestablished, it is possible to operate the elevator through the manual controller 255. As soon as the elevator is started into operation the counter electro-motive force relay 205 opens the circuit to the door operating control system.

The method of operation of a hydraulic elevator having the diagram of connections illustrated in Fig. 8 will now be described.

It should be understood that these elevators are standard apparatus and that the water valve operating switch 305 is found on all elevators of this type as well as the operating lever located by the coil 393 as has previously been explained. Under normal conditions the floor registering switch 374 is closed and the coil 373 is energized due to the fact that there is a circuit through the wire 300 and through the wire 365 to the contact 366, from thence through the bridging member of the relay 353 to the contact 372, through the coil 373 and the wire 331 to the wire 304, the wire 304 being connected to the wire 301 forming the other terminal of the circuit. In other words, the relay 353 is always in its upper position, closing the circuit between the contacts 366 and 372 and between the contacts 352 and 363 except under abnormal conditions which will hereinafter be explained.

With the relay in this position and with the car in any position, the car is started by operating the water control switch (not shown) which opens the switch 305 and disconnects the control mechanism for the door operating device. This mechanism remains disconnected until the elevator is stopped by closing the water control valve which closes the switch 305. The operator can then move the door controller 340 from the closed position $x-x$ to the open position $y-y$ and in so doing establishes connections between the contacts 341 and 343. A circuit is thus established through the wire 300 to the wire 365, to the contact 343 through the segments 380 of the contact 341, to the coil 351 of the opening relay 315, and from thence to the contact 352 across the bridging member of the relay 353 to the contact 362, through the wire 361 to the opening relay switch 360, and from thence to the wire 301, thus completing the circuit.

The relay 315 being lifted due to its coil being energized, closes the circuit composed of the wire 300, the contact 331, the bridging member of the closing relay 316, the contact 322, the armature 54, the contact 318 of the opening relay 315, the bridging member of that relay, the contact 313, the brake coil 50, the series field 53 and the wire 304. This opens the brake on the door operating mechanism and energizes the armature 54, causing the door to be opened.

During the time the door is opened the closing limit 358 is closed and the opening limit 360 is open as has previously been explained. The opening limit switch 360 in opening breaks the circuit to the coil 351 allowing the relay 315 to open and thus interrupting the operation as has previously been explained. The door can then be

closed by a similar actuation of the relay 316 which need not be explained, the operation being similar to that already explained in the case of the electrically operated elevator.

In the event that the elevator door is left open with the controller 340 in the position $y-y$ there is a possibility in a hydraulic elevator that the elevator will settle due to the 10 water leakage in the hydraulically operated mechanism thereof. As soon as the elevator settles sufficiently to disturb the proper contact between the projection 36 of the closing driving strip 78, the floor registering relay 15 374 is operated as has previously been explained. The opening of this relay opens the circuit to the coil 373 of the interlock relay 353 thus opening the circuit to the opening relay coil 351 and closing the circuit 20 to the coil 354 of the closing relay 316 through the contacts 368 and 370. The closing relay is therefore pulled upwardly even with the controller in the open position $y-y$, thus starting the armature 54 and closing 25 the door, the closing movement being stopped by the limit 358 in the usual manner.

It will be noted that the projections 36 and 37 are of unequal length, the object of this being to allow the closing projection 37 to close the door even after the driving strip 78 has broken connection with the projection 36.

We claim as our invention:—

- 35 1. An elevator door operating mechanism comprising a frame, a motor, a main shaft turning in bearings in said frame, means connecting said motor to said shaft, a crank on said shaft, a cross-head sliding in said frame, a crank pin block carried on said crank and sliding in said cross-head at right angles to the line of motion of said cross-head, and means by which said cross-head opens and closes the elevator door.
- 40 2. An elevator door operating mechanism comprising a frame, a motor, a main shaft turning in bearings in said frame, means connecting said motor to said shaft, a crank on said shaft, a cross-head sliding in said frame, a crank pin block carried on said crank and sliding in said cross-head at right angles to the line of motion of said cross-head, strips for driving said door carried by said cross-head, and means by which the 45 movement of said crank pin block opens and closes said strips with relation to each other.
- 45 3. An elevator door operating mechanism comprising a frame, a motor, a main shaft turning in bearings in said frame, means connecting said motor to said shaft, a crank on said shaft, a cross-head sliding in said frame, a crank pin block carried on said crank and sliding in said cross-head at right angles to the line of motion of said cross-head, fingers pivoted in said cross-head and

resting on said crank pin block in such a manner as to be actuated thereby, and two driving strips each carried by one of said fingers.

4. In combination, an elevator door, 70 mechanism for closing the door, a spring through which said mechanism closes said door, and means for stopping said mechanism whenever the pressure on said spring exceeds a predetermined value. 75

5. In combination, a building structure, doors sliding in said structure, an elevator car moving in a vertical hatchway past said doors, a separate means carried in said structure for opening each of said doors, 80 a projection carried by each of said means, two driving strips carried on said car for engaging said projection, said strips being normally separated to allow clearance with said projection, mechanism for forcing said strips together to grip said projection, and means for stopping said mechanism if said strips fail to touch said projection at the proper point. 85

6. In a door opening device adapted to 90 grip and move a projection operating an elevator door, two strips so placed as to pass on either side of said projection when the elevator car registers with a floor, and means for actuating said strips to move the door, 95 said strips being formed of relatively thin and elastic material.

7. In a door opening device adapted to 100 grip and move a projection operating an elevator door, two strips so placed as to pass on either side of said projection when the elevator car registers with a floor, and means for actuating said strips to move the door, 105 said strips being formed of relatively thin and elastic material and so secured that they can be torn away without injury to the remainder of the device. 110

8. In a door opener, a frame, walls forming a slide in the bottom of said frame, a cross-head moving in said slide, members 110 projecting from said cross-head at some distance above said slide, said members also projecting through a slot in said frame, and walls inclosing said slide below said slot to retain oil about said slide. 115

9. In an elevator, a door operating mechanism, actuating means for causing said mechanism to function and a counter electro-motive force relay connected across an armature actuated by the motion of the elevator for rendering said mechanism inoperative at all times while said elevator is in motion. 120

10. In an elevator door operating mechanism, a motor, a crank, means by which said 125 crank operates the elevator door, limit switches for stopping said motor at either end of the travel of said crank, and an interrupted gear through which said motor drives said crank, said gear being of such 130

proportions that it moves out of mesh if said limit switches fail to function.

11. In an elevator, a car controller located in the car and manipulated by the operator, a door controller located in the car and manipulated by the operator, and means for rendering the door controller operative only

when said controller is in the neutral position.

In testimony whereof, we have hereunto set our hands at Los Angeles, California, this 17th day of May, 1919.

LUTHER E. GROAT.
